UNITED STATES PATENT OFFICE.

CHARLES A. FOX, OF NEW YORK, N. Y.

COLLAPSIBLE BOX.

Application filed November 8, 1923. Serial No. 673,573.

To all whom it may concern:

Be it known that I, CHARLES AUGUSTUS Fox, a citizen of the United States, and a resident of the city of New York, borough 5 of Manhattan, in the county and State of New York, have invented a new and Improved Collapsible Box, of which the following is a full, clear, and exact description.

10 This invention relates to improvements in receptacles and has particular reference to a collapsible box.

The present invention is designed particularly as an improvement over my United 15 States Patent No. 1,463,074, dated July 24, 1923, and has for one of its objects the provision of a box of comparatively inexpensive construction, which may be readily collapsed and extended to operative position and

20 which, when in the latter position, will afford a convenient and relatively rigid container for various articles of merchandise.

Another object is to provide a box in which the main portion including the top 25 and bottom sections thereof are formed from a single sheet of material with a collapsible inner lining attached to one section and held in extended position by a portion of said section.

30 The above and other objects will appear more clearly from the following detail description when taken in connection with the accompanying drawings, which illustrate a preferred embodiment of the inventive idea.

In the drawings—

Figure 1 is a plan view of the box in partially open position;

40 Figure 2 is a section on the line 2—2 of Figure 1;

Figure 3 is a section on the line 3—3 of Figure 2;

Figure 4 is a section on the line 4—4 of Figure 1; and

45 Figure 5 is a plan view of the box in its collapsed position.

In the construction of the box a single sheet of suitable material, such as cardboard or the like, is employed in forming the bottom and top sections, generally indicated by the numerals 6 and 7, respectively, said sections being joined by a side wall portion 8 which is common to both sections and which forms a hinge connection therebetween.

50 The bottom section 6 further includes the side wall 9 opposite the wall 8 and the end

walls 10, adjacent ends of the walls 9 and 10 being provided with extensions 11 and 12, respectively, which are arranged in overlapping relation and secured by means of 60 suitable fasteners 13 to form reinforced and rigid corners. At the opposite end of each of the end walls 10 the material of which the box is formed is cut to provide a locking tongue 14 for a purpose which will presently 65 appear.

An inner lining 15 for the bottom section 6 is provided and is formed of two strips of material having adjacent ends overlapped and secured together by suitable fasteners 70 16 (see Figure 2). The width of the lining 15 is greater than the depth of the side and end walls 9 and 10 of the section 6 so that a considerable portion of the lining will extend above the top edge of said section when the box is in operative position. In order that the lining 15 may be collapsed, as shown in Figure 5, the ends of said lining are scored or creased, as indicated at 17, intermediate the ends thereof so that said ends 80 can be folded inwardly and the sides of said lining collapsed one upon the other, as clearly indicated in Figure 5. One of the sides of the lining 15 is secured to the front side wall 9 of the section 6 by suitable fasteners 85 18 so that the lining will be permanently attached to the section both when extended and collapsed. At the junction between the ends and free side of the lining 15 the lining 15 is provided intermediate its upper and 90 lower edges with slots 19 for receiving the locking tongues 14 formed upon the ends of the side walls 10 so as to maintain the lining 15 in its extended or operative position.

The top section 7 of the box includes the 95 end walls 20 and front or side wall 21 which have adjacent ends overlapped and secured together by fasteners 22, as clearly shown in Figures 1 and 5, said adjacent ends being suitably scored to permit of a folding thereof, as shown in the latter figure, when the box is collapsed. The portions 23 of the end walls 20 which overlap the side wall 8 common to both of the sections 6 and 7 are secured to said side wall by fasteners 24 and 100 105 are scored or creased, as indicated at 25, to permit of folding of said portions 23, as shown in Figure 1. By scoring each portion 23, as indicated, said portion will fold over upon the wall 8 and against the end portions 110 of the free end of the inner lining 15 when the box is in closed position.

The side wall 21 of the top section 7 is provided with an extension 26 which, when the top section is folded over upon the bottom section and lining 15, will project between the secured side of said lining and the side wall 9 of the bottom section. In this manner the top section 7 will cooperate with the lining 15 to preclude the possibility of unauthorized persons removing the contents of the box without injuring the same or destroying the sealing means which may be employed in locking the box in closed position.

What is claimed is

15. 1. In a collapsible box, bottom and top sections hingedly connected and each section including side and end walls, an inner collapsible lining secured to a wall of one section and of a greater width than the walls of said sections, and means forming a part of one of said sections and engageable with said lining to maintain the same in an extended position.
20. 2. In a collapsible box, bottom and top sections hingedly connected and each section including side and end walls, an inner collapsible lining secured to one of said sections and extending beyond the walls thereof, said lining being provided with slots at a point remote from its attachment to said section, and locking tongues carried by the end walls of the section to which said lining is secured and engageable in the slots in said lining to maintain the lining in extended position.
25. 3. In a collapsible box, bottom and top sections hingedly connected and each having side and end walls, an inner lining secured to a side wall of said bottom section and of a width substantially equal to the combined

thicknesses of said side and end walls, said lining including sides and ends, the latter of which are scored to permit said ends to be folded, said lining being also provided with slots, and locking tongues carried by the end walls of said bottom section and engageable in said slots to maintain said lining in an extended position.

4. In a collapsible box, bottom and top sections formed of a single sheet of material scored to provide an intermediate portion forming a hinge connection between said sections and also providing a side wall common to both of said sections, a collapsible inner lining secured to said bottom section and capable of being extended to a position in engagement with said intermediate portion when the sections are in closing position, and means carried by one of said sections and engageable with the lining to maintain the same in its extended position.

5. In a collapsible box, bottom and top sections formed of a single sheet of material scored to provide an intermediate portion forming a hinge connection between said sections, said bottom and top sections including end walls also formed by scoring said sheet of material, portions of said side walls overlapping said intermediate portion, means for securing said overlapping portions to said intermediate portion, locking tongues cut from said overlapping portions and forming parts of the end walls of one of said sections, and a collapsible lining secured to the latter section and engageable by said locking tongues when said lining is in its extended position to maintain said lining in such position.

CHARLES A. FOX.
